UNITED STATES PATENT OFFICE.

CHARLES W. WESTENFELTER, OF SPRINGFIELD, OHIO.

DENTIFRICE.

1,112,180.

Specification of Letters Patent.

Patented Sept. 29, 1914.

No Drawing.

Application filed March 8, 1913. Serial No. 752,854.

To all whom it may concern:

Be it known that I, CHARLES W. WESTENFELTER, a citizen of the United States, residing at Springfield, in the county of Clark and State of Ohio, have invented certain new and useful Improvements in Dentifrices, of which the following is a specification.

This invention relates to new and useful improvements in dentifrices, and has for its principal object to provide such a dentifrice with an ingredient that will readily indicate to the user the condition of his or her mouth: that is, whether the mouth is in an acid or alkaline condition.

Another object of the invention is to include in the dentifrice a combined coloring and indicating agent which is of such a character that any acid within the mouth of the user will neutralize the coloring properties of the agent and thereby readily indicate the condition of the mouth.

In forming this mixture I employ any suitable body, either liquid or powder, and add thereto a combined coloring and indicating agent. In the perfumed embodiment of my invention the body preferably consists of the following ingredients:

30	Tincture myrrh	12 oz.
	Precipitated chalk	2 lbs.
	Glycerin	24 oz.
	Alcohol	2 $\frac{3}{4}$ lbs.
	Bicarbonate of soda	$\frac{1}{2}$ oz.
35	Hydroxid of soda	$\frac{1}{2}$ oz.
	Oil of peppermint	4 drams.
	Saccharin	40 grains.
	Water	

To the above mentioned ingredients I add my combined coloring and indicating agent which, in this instance, consists of 15 grains of phenolphthalein. The word "phenolphthalein" is the common or trade name which has been adopted in place of either of the following chemical names, "dioxytriphenylphthalid" or "dihydroxyphthalophenone". This agent is well known, and consists of carbon, hydrogen and oxygen in the following proportions, $C_{20}H_{14}O_4$. In preparing a quantity of this mixture all of the ingredients, except the water, are mixed together in the proportions named, and then enough water is added to this mixture to make one gallon of the dentifrice. By combining "phenolphthalein" with the other ingredients, the mixture is given a red color

and, while I prefer to use this indicating agent, any other agent may be employed which will be neutralized by contact with an acid, and any other body such as powder may be employed if desired, or any other suitable indicating agent may be employed.

The natural condition of the human mouth is alkaline, but very few persons have a natural mouth, as most of them are in an acid condition a greater part, if not all, of the time. When this dentifrice is introduced into the mouth the organic acids which are present in the mouth, will decolorize the phenolphthalein and at the same time the alkalis which are present in the dentifrice will tend to neutralize the acids and to restore the mouth to its natural condition, that is, an alkaline condition. As this restoration is accomplished the decoloration will diminish and when the mouth is wholly restored to an alkaline condition the dentifrice will retain its original color, which is pink, but so long as there is any considerable amount of acid present in the mouth the dentifrice when discharged from the mouth will be colorless. Of course, if the mouth is in an alkaline condition when the dentifrice is first introduced there will be no decoloration but the dentifrice will retain its color.

As above stated the extent of decolorization of the dentifrice depends upon the amount of acid in the mouth. If the acid is present in any considerable quantities the solution will be entirely decolorized. If present only in small quantities the change of color of the solution will be less marked but will indicate, by this graduating of the coloring, the amount of acid present and the correction of the same. Obviously, by varying the amount of alkali contained in the solution the sensitiveness of the same to the acid can be varied and if desired the amount of alkali can be reduced to such an extent that only a slight acidity will completely decolorize the solution but this is undesirable and I prefer to have such a quantity of alkali in the solution that it will require considerable acidity to completely decolorize the same. It will furthermore be observed that I have formed a dentifrice in which none of the ingredients are injurious to the teeth. On the contrary, the ingredients employed assist in preserving the teeth. The tincture of myrrh hardens the gums, the chalk cleans and polishes the teeth, the glycerin is used as a sweetening agent and

also to increase the specific gravity of the dentifrice, the alcohol is used as an anti-septic and also as a hardener for the gums; bicarbonate of soda is a solvent and anti-acid, the hydroxid is an antiacid and an alkali, the oil of peppermint is used for flavoring the dentifrice, and the saccharin is used for sweetening the same.

Having thus fully described my invention,
19 what I claim as new and desire to secure by
Letters Patent, is:—

1. In a dentifrice, a mixture consisting of a body, and an agent for indicating an acid or alkaline condition of the mouth.
- 15 2. In a dentifrice, a mixture consisting of a body, and an agent for coloring the dentifrice and indicating an acid or alkaline condition of the mouth.
3. In a dentifrice, a mixture consisting of a body, and a coloring agent adapted to have its coloring properties neutralized by acid in the mouth.
- 20 4. In a dentifrice, a mixture consisting of a body, and an agent consisting of phenolphthalein for indicating an acid or alkaline condition of the mouth.
- 25 5. In a dentifrice, a mixture consisting of

tincture of myrrh, precipitated chalk, glycerin, alcohol, bicarbonate of soda, hydroxid of soda, oil of peppermint, saccharin, water and an agent for indicating an acid or alkaline condition of the mouth.

6. In a dentifrice, a mixture consisting of tincture of myrrh, precipitated chalk, glycerin, alcohol, bicarbonate of soda, hydroxid 30 of soda, oil of peppermint, saccharin, water, and an agent consisting of phenolphthalein for indicating an acid or alkaline condition of the mouth.

7. In a dentifrice, a mixture consisting of 40 12 oz. tincture of myrrh, 2 lbs. precipitated chalk, 24 oz. glycerin, 2 $\frac{3}{4}$ lbs. alcohol, $\frac{1}{2}$ oz. bicarbonate of soda, $\frac{1}{2}$ oz. hydroxid of soda, 4 drams oil of peppermint, 40 grains saccharin, water, and an agent consisting of 45 phenolphthalein for indicating an acid or alkaline condition of the mouth.

In testimony whereof, I affix my signature in presence of two witnesses.

CHARLES W. WESTENFELTER.

Witnesses:

F. W. SCHAEFER,
HARRIET L. HAMMAKER.
